NILS A. WAHLBERG, OF WILKINSBURG, PENNSYLVANIA, ASSIGNOR TO WESTINGHOUSE ELECTRIC & MANUFACTURING COMPANY, A CORPORATION OF PENNSYLVANIA

STRAIN CLAMP

Application filed July 30, 1927. Serial No. 209,438.

My invention relates to clamps, and particularly to strain, dead-end or jumper clamps for supporting high-voltage transmission-line conductors.

One object of my invention is to provide a clamp, of the above indicated character, that shall facilitate mounting of the conductor relatively thereto and that shall assist in holding the conductor temporarily while being clamped in position.

Another object of my invention is to provide a transmission-line clamp that shall be provided with mounting and lifting means at convenient positions adjacent to the intermediate section of angularly related clamping or supporting arms thereof.

Another object of my invention is to provide a conductor clamp that shall be compact in construction and embody a substantially minimum amount of material.

Another object of my invention is to provide a clamp that shall be simple and durable in construction, economical to manufacture and effective in its operation.

With such objects in view, as well as other advantages which may be incident to the utilization of the improvement, the invention consists in the parts and combination thereof hereafter set forth and claimed, with the understanding that the several necessary elements constituting the same may be varied in proportion and arrangement without departing from the nature and scope of the invention.

Accordingly, in practicing my invention, I provide a clamp embodying an arm for substantially parallel relation to a span section of the conductor, an arm for angular relation thereto, positioning lips adjacent to the ends and intermediate portion of the clamp, clamping means between the ends and intermediate lips, and lifting and mounting means, adjacent to the intersection of the arms, in such combination and arrangement as to attain the objects of my invention, and further, to provide a clamp that is, in general, an improvement over similar devices heretofore employed.

Figure 1, of the accompanying drawing, is a view, in side elevation, of a clamp con-

structed in accordance with my invention, with parts omitted and portions of a conductor and a mounting link for cooperation therewith broken away for clearness, and

Fig. 2 is a bottom plan view of the device shown in Fig. 1.

The device comprises, in general, a preferably single integral metal casting 2 embodying angularly related arms 3 and 4, lifting means 5, conductor-receiving seat portions 7 and 8, in the arms 3 and 4, respectively, positioning lips 10, 11 and 12, a mounting link 14 and clamping members 15 and 16 associated with the arms 3 and 4, respectively.

The arm 2 is disposed parallel to a span section 17 of a transmission-line conductor, and the arm 4 is in parallel relation to a portion of a dead-end or jumper section 18 of the conductor, the seat portions 7 and 8 being of trough-like character disposed on their sides, in the arms 3 and 4, for the ready reception of the conductor, by relatively moving the casting 2 and the conductor laterally toward each other.

The lips 10, 11 and 12 are also preferably of trough-like character and displaced about their longitudinal axes at right angles relative to the axes of the seat portions 7 and 8 to temporarily hold the conductor, while the clamping members 15 and 16 are being placed in position.

The lip 11 is preferably curved in accordance with a seat portion 19 joining the arms 3 and 4 and, similarly to the lip 10, projects upwardly at the side of the conductor opposite to that at which the main body of the casting 2 is disposed. The lip 12 projects downwardly or in reverse direction to the lips 10 and 11.

A plurality of pairs of openings 21, in the arms 3, are provided for the reception of bolts 22 which, with nuts 23, hold the clamping members 15 in position. Similar openings 24 are provided in the arm 4 for cooperation with bolts 25 and nuts 26 for holding the clamping members 16 against the jumper conductor section 18 on the arm 4.

The members 15 may be integrally connected to each other and adapted for co-

operation with a common clamping shoe over the conductor, as may also be the clamping members 16, in accordance with usual and well known practice.

5 The link 14, only a portion of which is shown, is connected, by a bolt 28 and a nut 29, to an apertured boss 30 on the casting 2 adjacent to the lifting means 5 which is preferably in the form of a loop or eyelet.

10 In mounting the conductor, the jumper conductor section 18 is preferably first placed under the lip portion 12 and bent around the seat portion 19 behind the lip 11, the lips 10, 11 and 12 assisting in holding the conductor in position, while the clamp members 15 and 16 are being mounted.

15 After the parts have been thus assembled, the device may be easily elevated to its operative position, on a tower or similar main supporting structure, by means of a hook disposed in the lifting loop 5 and connected to a block-and-tackle device on the tower.

20 The lips 10, 11 and 12, being spaced relatively far apart on the side of the conductor opposite the main body of the clamp, hold the conductor from lateral displacement therefrom, during the mounting of the clamp substantially as well as a continuous wall but, in contradistinction to such a wall, facilitate the positioning of the conductor in the clamp and render the construction of the permanent clamping parts made effective and their assembly easier.

25 Having a lip at each end of the clamp and clamping means between each end lip and the intermediate lip 11 are also, features which, in combination with the side-groove portions 7 and 8, the lifting means 5 and other parts, render the structure of manufacturing, economical, assembling and operating advantages in an important field.

30 The relative inaccessibility of the high tower or poles on which such clamps are mounted, the adverse weather conditions, such as rain, wind, snow and sleet, under which they must operate and the exacting requirements of the service which they are expected to give, render improvements of the character outlined highly desirable.

35 I claim as my invention:

1. A clamp comprising a channeled arm for substantially parallel relation to a span section of a transmission-line conductor, a channeled arm constituting a continuation of said arm but disposed in angular relation thereto, means for positioning the conductor including a lip adjacent to the outer end of each of said arms, means disposed between each of said lips and the intersection of the arms for clamping the conductor and means at one side only of one of said channel portions for mounting the clamp.

2. A clamp comprising an arm for substantially parallel relation to a span section of a transmission-line conductor, an arm for an-

gular relation thereto, means for positioning the conductor including a lip adjacent to the outer end of each of said arms and a lip adjacent to the intersection of the arms, and means disposed between each of said end lips and the intermediate lip for clamping the conductor.

3. A clamp comprising an arm for substantially parallel relation to a span section of a transmission-line conductor, an arm for angular relation thereto, and means for positioning the conductor including similarly-projecting lips adjacent to the outer end of said span arm and to the intersection of the arms, respectively, and an oppositely-projecting lip adjacent to the outer end of said angular arm.

4. A clamp comprising an arm for substantially parallel relation to a span section of a transmission-line conductor, an arm for angular relation thereto, conductor-positioning means on each of said arms and a clamp-lifting loop portion and means for receiving a relatively movable clamp-mounting element adjacent to the intersection of the arms.

5. A clamp comprising an arm for substantially parallel relation to a span section of a transmission-line conductor, an arm for angular relation thereto, each of said arms having a trough-like conductor-receiving seat portion disposed on its side, and trough-like conductor-positioning portions adjacent to the outer ends, and to the intersection, of the arms disposed at angles about the longitudinal axes thereof relative to the axes of said seat portions.

6. A clamp comprising an arm for substantially parallel relation to a span section of a transmission-line conductor, an arm for angular relation thereto, a curved portion joining said arms, each of said arms having a trough-like conductor-receiving seat portion disposed on its side, a relatively short conductor-positioning lip adjacent to the outer end of each of said arms projecting oppositely to the other lip, a lip adjacent, and substantially conforming to said curved portion and means for clamping the conductor at a plurality of positions between each of said end lips and said intermediate lip.

7. A clamp comprising an arm for substantially parallel relation to a span section of a transmission-line conductor, an arm angularly related thereto, a gradually curved portion between said arms, a single continuous conductor-receiving channel portion extending along one of said arms, along said curved portion and along the other arm, means for holding the conductor in position and means at one side only of said channel portion for mounting the clamp.

8. A transmission-line clamp comprising a body member including a channel portion for receiving a conductor therealong, said body having an outwardly-flared channel-like lip

adjacent to each end angularly disposed about its axis relative to the other end lip, means for holding the conductor in position and means at one side only of said channel portion for mounting the clamp.

5 9. A transmission-line clamp comprising a body member for receiving a conductor therealong, said body having an outwardly-flared channel-like lip adjacent to each end angularly disposed about its axis relative to the other end lip and a lip intermediate said end lips, and means for holding the conductor in position.

10 10. A transmission-line clamp comprising a body having angularly related portions for receiving a conductor therealong, said body having an outwardly-flared channel-like lip adjacent to each end angularly disposed about its axis relative to the other end lip and a 15 lip adjacent to the intersection of said angularly-related body portions, and means for holding the conductor in position.

15 11. A transmission-line clamp comprising a body having angularly related portions joined by a curved portion and a single continuous conductor-receiving channel portion extending along all of said portions, said body having an outwardly-flared channel-like lip adjacent to each end angularly disposed about 20 its axis relative to the other end lip and a lip adjacent to said curved portion, and means for holding the conductor in position.

25 In testimony whereof, I have hereunto subscribed my name this 20th day of July, 1927.
